OTTO WOHLRABE AND VICTOR STEPHAN, OF PLAUEN, GERMANY.

STEREOTYPE-PLATE-CASTING MACHINE.

Application filed May 12, 1924. Serial No. 712,785.

To all whom it may concern:

Be it known that we, OTTO WOHLRABE and VICTOR STEPHAN, both citizens of the German Republic, and residents of Plauen, 5 Saxony, Germany, have invented certain new and useful Improvements in Stereotype-Plate-Casting Machines, of which the following is a specification.

Our invention relates in general to stereoplate casting-machines, but more especially it relates to the casting-mould for or of such machines; one part of our invention concerns the introduction of the metal into the mould; another part concerns the retaining of the metal therein, i. e. a closing device for the mould, and a third part concerns certain means for actuating this device, as is all fully described hereinafter.

Before entering into details we deem it necessary to give certain introductory explanations in order to facilitate comprehending the gist of the invention immediately it has been disclosed.

Hitherto the mould for or of stereotype-plate casting-machines has been arranged either vertically or horizontally. The object in the first case was to utilize the advantage that the mantle of the mould can be easily moved off the casting core, as no weight-work is required therefor. But the advantage is more or less compensated for by the disadvantage that it is necessary to run the casting metal into the mould from the upper frontal side thereof whereby a lost or dead head is produced and the necessity is entailed to mend considerably the printing plate.

In the case of horizontal casting moulds the mending can be obviated by causing the metal to run into the mould at a narrow longitudinal side thereof, but then the necessity arises to lift the mantle towards the core, when the mould is to be closed, that the pretty considerable weight of the mantle must be overcome by a corresponding expenditure of power and work.

Another drawback common to all these known arrangements consists therein that the casting metal enters into the mould in

such a way that the air contained in the 50 mould must try to find its way outwards along the surface of the flowing-in metal because this latter rushes into the mould from above in the entire breadth thereof. It then occurs oftentimes that more or less 55 large air-bubbles cannot escape prior to the metal solidifying, whereby the casting is rendered porous.

Now, in order to obtain and combine the advantages offered by the known arrangements, but to obviate at the same time the disadvantages or drawbacks thereof, we have so devised the casting-mould (which may be a vertical or a horizontal one) that the metal can be run thereinto simultaneously at its 65 two small or narrow longitudinal sides, whereby the following advantages are obtained:

First of all the casting metal flows into the mould in two separated currents, between which the air can escape easily in upward direction without having any opportunity to form pores in the metal. And as regards the product, printing plates can be, and are, produced which do not require any 70 mending, such, for instance, as the turning off of a lost or dead head. In the case of the employment of vertical moulds the advantage may be utilized that no expenditure of work worth mentioning is required 75 to convey the ladle to the mould.

But what has been stated in the preceding two paragraphs relates only to a part of our invention. Another part relates to means for closing in proper time the communication between the ladle and the mould, the intention being to keep liquid the metal at this particularly sensitive part of the machine while this latter is in operation, or, in other words, to prevent it from cooling 80 down in the interval of time between two casts, that is to say, during that time in which the printing-plate cast solidifies. That occurs easily if rotary slides or longitudinal slides are employed as closing means 85 for the mould, the liquid metal then remaining in the supply-channel in the proximity of the plate just cast. The employment of

those kinds of slides, or mould closing means respectively, is the cause of many interruptions of service, and besides, the life of the casting machine is shortened and finishing 5 the printing plates is retarded.

We have devised means to overcome the just mentioned drawbacks; the object proper of these means (which are fully described hereinafter) is to force back the metal remaining 10 in the supply-channel after the casting-mould has been closed; in other words: that metal is removed from the proximity of the mould until the printing-plate cast has solidified. That procedure is 15 the more desirable as then the first metal particles arriving at the mould at the next casting operation get thereinto in hot and liquid state and are thus able to fill up the minute cavities of the matrix, as necessary. 20 We attain the object now in view by using specially devised valve-pistons instead of the usual rotary or longitudinally movable slides, those pistons closing the mould in such a manner that the superfluous metal 25 is forced back into the ladle, as will appear more distinctly from the detailed part of this specification following.

Our invention is illustrated by way of example in the accompanying drawing in 30 which Figure 1 is a horizontal section of the supply channel provided to conduct the liquid metal into the mould; in other words: it is a horizontal section of the parts forming said channel. Figure 2 is a front-view 35 of a valve-piston as mentioned above. Figure 3 is a vertical section of this piston in the plane A—A of Figure 1. Figure 4 is a vertical section of certain parts of a stereotype plate casting machine which are shown 40 in order to facilitate understanding the invention; the plane of section is B—B of Figure 1, and the figure is drawn on a reduced scale. Figure 5 is a diagrammatic illustration 45 of the driving rods for two valve-pistons of the kind in question, according to line C—C of Fig. 4. Fig. 6 is a section through the machine according to line D—D of Fig. 4.

The casting mould consists in known manner 50 of a core 1 and a mantle 2, between which a space corresponding to the shape of the printing plate to be cast is left. The core and the mantle are provided with jackets through which cooling water or another suitable cooling liquid is caused to flow. The matrix is held fast at the mantle by a lock 3. The casting mould shown by way of example is a vertical one (Fig. 4) and the mantle is therefore, swingable on a vertical axis. The casting metal shall be conducted 55 into the above-mentioned space at the two small or narrow longitudinal sides or surfaces of the mould where suitably shaped slots are provided for this purpose. These 60 slots communicate with slots 4 and 4' (Figs. 65

1, 4 and 5). The mould is thus filled uniformly and quickly and the casting produced is of excellent quality, requiring no mending whatever.

The position of the slots or passages 4 and 4' with respect to the basin or melting pot 5 containing the liquid metal appears from Fig. 5, in which the side walls of the basin are indicated by dot-and-dash lines, as shown. Concerning the casting mould, the position of the supply-channels is shown best in Fig. 4. The core of the mould communicates with the basin or melting pot 5 through an intermediate member 6. There are two such members, one on either side of the two small or narrow longitudinal sides of the mould, and in each thereof two communicating recesses are provided, of which one forms the passage 4 and the other serves as space for the reception of the valve-piston 85

7. Each of these pistons, of which there are two (Fig. 5), is formed by a cylindrical body having a conical frontal head, as shown in the lefthand part of Figure 1. One side of the piston is flattened, as at 8, Fig. 1; the rear end of the piston is flattened at four sides (Fig. 3) and a slot is milled thereinto for the reception of the end of a connecting rod 9 by which the piston is reciprocated as hereinafter described. The piston and the connecting rod are connected with each other by a bolt 11 (Fig. 3) and by a pin 10 securing the bolt in its position in the piston. 95

The milled slot provided in the piston for the junction thereof with the connecting rod is at its inner end shaped obliquely as indicated by the lines 12 and 12' in Fig. 5, the purpose being that one side of the piston is able to take up fully the lateral pressure exerted on the piston by the connecting rod 105 when the mould is closed.

Opposite the conical end of the piston 7, or 7' respectively, the member 6 is recessed correspondingly so that there is nearly no clearance when the piston has arrived at the end of its path, the liquid metal being then forced away out of the valve space nearly completely into the basin or pot 5 through the channel 4. 110

The flattened side of the piston, or of each of the pistons 7 and 7' respectively, is just over the matrix lock 3 behind which is a cavity 21 into which extends a projection of the piston which forms a part of the guiding means for the piston. 115

The metal supply channel 4 terminates in front of the conical end of the piston so that it remains open during the entire path of the piston and is closed only at the end of this path, the orifice of the supply channel 125 being thus able to receive liquid metal also while the piston is moving in that direction, at the end of which path the channel 4 is closed. The liquid metal forced into the channel 4 during this movement of the pis- 130

ton, and remaining therein until the next casting operation proceeds, remains liquid and will again flow briskly into the space in front of the piston as soon as this latter is withdrawn, there being now no risk whatever that that metal will solidify prematurely, i. e. before the valve-piston is withdrawn.

In order to control the two pistons reliably from a common point, we prefer to make use of the arrangement and combination of parts shown in Fig. 5, in which either piston is connected by a rod 9, or 9' respectively, with a bell-crank lever 15/16, or 15^{''}/16^{''} respectively, the two levers being connected with each other by a rod 17. The bell-crank lever 15/16' has a third arm 18 to which is hinged a rod 19 by which the bell-crank levers are turned in the appropriate point of time from the position shown in full lines into that indicated by dotted lines, and reversely. In other words: The bell-crank levers 15/16' is turned into the position 15^{''}/16^{''}, and the bell-crank lever 25 is turned into the position 15^{*}/16^{*}. It appears from Fig. 5, that the members 9 and 15 on one side, and the members 9' and 15' on the other side, co-operate like toggle-levers so that the closing-motion of the pistons 7 and 7' is effected with a considerable power.

We claim:

1. In a stereotype-plate casting machine, in combination: a casting mould having small longitudinal walls on opposite sides, and members having metal supply channels terminating at said walls.

2. In a stereotype-plate casting machine, in combination, a vertical casting mould having narrow longitudinal walls on opposite sides, and members having metal supply channels terminating at said walls.

3. In a stereotype-plate casting machine, in combination: a casting mould having small longitudinal walls on opposite sides, and members having metal supply channels terminating at said walls; a member located in front of each mould-supply channel and forming a space communicating therewith and extending practically at right angles thereto; a valve-piston arranged to reciprocate in said space and having a flattened side arranged to slide over the inlet aperture to the mould-supply channel; and a main supply passage also provided in said latter member and terminating in front of said piston-valve, substantially as set forth.

4. In a stereotype-plate casting machine, in combination, a vertical casting mould having narrow longitudinal walls on opposite sides, and members having metal supply channels terminating at said walls; a member located in front of each mould-supply channel and forming a space com-

municating therewith and extending practically at right angles thereto; a valve-piston arranged to reciprocate in said space and having a flattened side arranged to slide over the inlet aperture to the mould-supply channel; and a main supply passage also provided in said latter member and terminating in front of said piston-valve, substantially as set forth. 70

5. In a stereotype-plate casting machine, in combination: a casting mould having small longitudinal walls on opposite sides, and members having metal supply channels terminating at said walls; a member located in front of each mould-supply channel and forming a space communicating therewith and extending practically at right angles thereto; a valve-piston arranged to reciprocate said space and having a flattened side arranged to slide over the inlet aperture to the mould-supply channel; and a main supply passage also provided in said latter member and terminating in front of said piston-valve; a bell-crank lever connected with each of the two valve-pistons which are arranged to move in opposite directions; a rod connecting the free arms of said levers with each other, and means for actuating the said valve pistons by the intermediary of the said levers as set forth. 75 80 85 90 95

6. In a stereotype-plate casting machine, in combination: a casting mould having small longitudinal walls on opposite sides, and members having metal supply channels terminating at said walls; a member located in front of each mould-supply channel and forming a space communicating therewith and extending practically at right angles thereto; a valve-piston arranged to reciprocate in said space and having a flattened side arranged to slide over the inlet aperture to the mould-supply channel, and having at its opposite end a recess having an oblique inner end wall and being adapted to receive the end of a connecting-rod attached to said valve-piston in said recess, and means to actuate this rod; and a main supply passage also provided in said latter member and terminating in front of said piston-valve, substantially as set forth. 100 105 110 115

7. In a stereotype-plate casting machine, in combination, a vertical casting mould having narrow longitudinal walls on opposite sides, and members having metal supply channels terminating at said walls; a member located in front of each mould-supply channel and forming a space communicating therewith and extending practically at right angles thereto; a valve-piston arranged to reciprocate in said space and having a flattened side arranged to slide over the inlet aperture to the mould-supply channel, and having at its opposite end a recess having an oblique inner end wall and being adapted to receive the end 120 125 130

of a connecting-rod; a connecting-rod attached to said valve-piston in said recess thereof; a bell-crank lever connected with each of the two connecting rods; a rod connecting the free arms of said levers with each other, and means for actuating the

said valve-pistons by the intermediary of the said levers, as set forth.

In testimony whereof we affix our signatures.

OTTO WOHLRABE.
VICTOR STEPHAN.
